COMBINED CIGARETTE BOX AND LIGHTER

Herman G. Treiss, New York, N. Y., assignor to American Safety Razor Corporation, Brooklyn,
N. Y., a corporation of Virginia

Application December 21, 1953, Serial No. 28,140

Term of patent 14 years

(Cl. D85—2)

To all whom it may concern:

Be it known that I, Herman G. Treiss, a citizen of the United States, and a resident of the county of Bronx, city and State of New York, have invented a new, original, and ornamental Design for a Combined Cigarette Box and Lighter, of which the following is a specification, reference being had to the accompanying drawings, forming part thereof.

Fig. 1 is a perspective view of the combined cigarette box and lighter, showing my new design;

Fig. 2 is a plan view thereof as seen from the top;

Fig. 3 is a plan view thereof as seen from the bottom;

Fig. 4 is a rear end view thereof;

Fig. 5 is a side elevation thereof;

Fig. 6 is an exploded front end showing the lighter-carrying cover and the box;

Fig. 7 is a plan view showing the inside of the box; and

Fig. 8 is a plan view showing the underside of the lighter-carrying cover.

I claim:

The ornamental design for a combined cigarette box and lighter, as shown.
